UNITED STATES PATENT OFFICE

PAUL K. BASMADJIAN, OF PHILADELPHIA, PENNSYLVANIA; ARONSEAG BASMADJIAN
EXECUTRIX OF SAID PAUL K. BASMADJIAN, DECEASED

COVER FOR PICKLES, ETC.

Application filed September 4, 1928. Serial No. 303,842.

My invention relates to covers for containers holding relishes and other perishable food products.

The main purpose of my invention is to protect, to a maximum between servings from their containers, the surfaces of perishable food products sold from bulk.

A further purpose is to provide a follower preferably in the form of a float filling substantially the entire cross-section of the container and resting upon the surface of the food.

A further purpose is to cover the food by an excess of liquor and to float a protective cover upon the liquor.

A further purpose is to provide convenient means for removing surface water from a container.

A further purpose is to support a floatable cover for foods covered by liquid in suitable position for drainage within the container.

Further purposes will appear in the specification and in the claims.

I have preferred to illustrate one general form of my invention only showing two shapes and two materials thereof and selecting a form which has proved to be practical, efficient, simple and inexpensive and which at the same time well illustrates the principles of my invention.

Many articles sold in bulk by grocers and keepers of delicatessen stores are subject to injury through the formation of mould long before the quantity ordinarily exposed for sale has been sold. Pickles form so excellent an example of this within the knowledge of all such store keepers that I will use them as an illustration, intending them to be typical of the entire group of relishes and perishable foods to whose protection my invention is directed.

Figures 1 and 4 are top plan views of variant forms.

Figure 2 is a section of Figure 1 upon line 2—2, showing parts in elevation.

Figure 3 is a section of a float differing from that in Figure 2.

Figure 5 is a section of Figure 4 taken upon line 5—5.

Figures 6 and 7 correspond to Figure 5 but show the float in different positions.

In the best practice with which I am familiar pickles are ordinarily kept in a straight sided jar of the general character shown in Figures 1 and 2, are covered by brine and are protected by a top cover such as that shown in outline in Figure 2.

The increasing air space which becomes quite large before the jar is empty facilitates the growth of mould upon the surface of the pickles exposed or, where they are covered by brine, upon the surface of the brine. Such products as chow-chow usually have no covering of liquor. They are also subject to injury by formation of mould.

The formation of the mould gives a general appearance of uncleanliness and causes the food when withdrawn from the jar to appear to be in bad condition. This injury to the food is not confined to appearance alone, as the same causes which result in the accumulation of mould result also in discoloration and decay of some of the food, with the result that quite generally parts of such bulk foods are sent back to the wholesale grocer for replacement as unsalable.

I have discovered that the same type of straight sided jar now in use may be used without or with the same jar-top cover shown in Figure 2 to secure very complete protection of the bulk food products if the immediate surface of the food products be protected by a follower or cover resting upon the surface of the food or upon the surface of the liquor covering of the food.

This protection is very much more complete and effective in the case of foods covered by liquor if the follower be made in the

form of a float which does not become submerged in the liquor and which, therefore, when in position protects substantially the entire surface of the content.

- 5 One form is shown in Figures 1 and 2 where the jar 5 is cylindrical and of substantially uniform diameter and where the pickle content 6 is covered by a layer of brine 7 which supports a follower, preferably a float 8 covering substantially the entire brine surface. The extent to which the float covers the surface is, nearly, the measure of its usefulness. This extent of course depends in part upon the uniformity of the 15 diameter of the jar interior.

My invention relates to the process involved as well as to apparatus by which the process may be carried out.

The follower 9 is preferably made of glass 20 for much the same reasons as dictated the use of glass ordinarily in the manufacture of jars 5, namely because it is transparent and because it can be cleaned quickly, easily and effectively. The float is hollow at 10 25 and when made of glass is provided with a preferably integral handle 11.

In this form, in order that the liquor from the bath may not remain upon the upper surface of the follower if splashed upon it, I 30 convex the upper surface of the follower at 12. I also convex the lower surface at 13 so as to provide quick drainage of liquor from the lower surface as the follower is lifted from the surface to expose the content for serving.

In Figure 3 the float 10' is solid.

To make evident that the circular cross-section of the container is in no wise vital to the success of my invention and that the 40 convex float surface may be omitted while still securing a part of the advantage of my invention, I illustrate in Figure 4 a rectangular container 5' with a follower 9' also of rectangular cross-section, adapted to fill substantially the entire interior of the container. The handle here shown at 10' may be integral or not.

In this form the flat sides enable me to hang the follower on the sides by the handle 50 as in Figure 6, without leaving the follower extend far out into the jar and without using a long handle. The handle can be hooked over the side to support the float close against the side. See Figure 6.

55 The top is cupped at 13 so that the float may be pushed down in a liquid to cause the liquid to flow over the upper edge into the cup for quick and easy removal of excess liquid. While flattening of the follower bottom at 14 is not essential for this purpose it is of advantage as the bottom then interferes less with the normal level settling position of the solid content.

60 The cupped top preferably has a wall slope at 15 such that any liquid remaining

in the follower cup will drain when the follower is hung upon the side. Though with but little advantage from hanging the follower from the side in the earlier numbered views, the cupping of the top could be used to advantage in the forms shown in these views if its special advantages be desired.

In Figures 5-7 I show two additional features.

The use of glass is by no means essential to obtain results from my invention.

Solid covers may be followers merely for quasi solid materials—of the chow-chow order—or may be of wood or cork in order that they may float. Whatever the material, if the surface of the follower be injurious to the content or be apt unduly to soak up the content, it is desirable to cover the surface with a suitable paint or enamel to protect against this.

Obviously the protective feature of my invention would be carried out whether the follower rest upon a quasi solid content or float upon a covering liquor. It is also evident that a follower of the float variety would serve the follower function with a quasi solid content and would perform the additional floating function where a liquor covering has been provided.

With whatever shape of jar the invention be used there is an advantage in providing the usual top cover 16 for the jar in addition to the follower, as the inner surface of the jar and the upper surface of the follower will thus be protected against dust and dirt and against the intrusion of flies.

When a floating follower is used which substantially fills the cross-section of the jar interior and has sufficient side thickness so that the upper edge is not closely approached by the liquor of the content, there is no opportunity for flies to feed from the liquor content and I find the protection from flies to be very complete and effective.

I intend the language "parallel-sided" to refer to the circular form of jar as well as to one of polygonal section and to indicate that the elements cut by vertical planes through the center are substantially parallel.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:—

1. A parallel-sided jar for the reception of food in bulk and a follower adapted to fill substantially the entire cross-section of

the jar, having a cupped top for filling with liquid from the jar by over-flowing and removal of the liquid and a handle for the top extending from the bottom of the cup 5 above the cup level in order that the cup may be lifted without engagement of the hand with the cup contents.

2. A parallel-sided jar of rectangular transverse section, a rectangular follower 10 substantially filling the cross section of the jar and having a cupped top and a handle for the follower extending outwardly from the cupped top and adapted to hang the follower upon the side of the jar and drain 15 the cup from the follower.

CERTIFICATE OF CORRECTION.

Patent No. 1,818,924.

Granted August 11, 1931, to

PAUL K. BASMADJIAN.

It is hereby certified that the name of the executrix in the above numbered patent was erroneously written and printed as "Aronseag Basmadjian", whereas said name should have been written and printed as "Arouseag Basmadjian", as shown by the records of assignments in this office; and that the said Letters Patent should be read with this correction therein that the same may conform to the record of the case in the Patent Office.

Signed and sealed this 3rd day of November, A. D. 1931.

(Seal)

M. J. Moore,
Acting Commissioner of Patents.
